UNITED STATES PATENT OFFICE.

FRANK E. SWIFT, OF WASHINGTON, IOWA.

CONTINUOUS KILN.

SPECIFICATION forming part of Letters Patent No. 703,848, dated July 1, 1902.

Application filed September 10, 1901. Serial No. 74,944. (No model.)

To all whom it may concern:

Be it known that I, FRANK E. SWIFT, a citizen of the United States, residing at Washington, in the county of Washington and State of 5 Iowa, have invented certain new and useful Improvements in Continuous Kilns; and I do declare the following to be a full, clear, and exact description of the invention, such as will enable others skilled in the art to which to it appertains to make and use the same.

This invention relates to improvements in continuous kilns for burning brick, pottery, and other ware and for other analogous purposes.

15 The invention provides a continuous kiln more especially adapted for use in connection with furnaces using slack and other cheaper varieties of fuel, but also adapted to be used advantageously in connection with all types 20 of kiln-furnaces, the object in view being to secure the better heating of the kiln-chambers, the more equable circulation of the heat and flames, and the more thorough and uniform burning of the brick or other ware, as 25 well as to insure economy in firing and the effective regulation of the heat to suit the character of ware under treatment.

With this and other objects in view the invention consists of certain novel features of 30 construction, combination, and arrangement of parts, as will be hereinafter more fully described, and particularly pointed out in the appended claims.

In the accompanying drawings, Figure 1 is 35 a top plan view of a continuous kiln embodying my invention. Fig. 2 is an end elevation of the same looking in the direction of the arrow from the line 2 2 in Fig. 1. Fig. 3 is an elevational view of three of the kiln-chambers looking in the direction of the arrow from the line 3 3 in Fig. 1. Fig. 4 is an irregular vertical cross-section through the same kiln-chamber on the line 4 4 of Fig. 1. Fig. 5 is 40 a horizontal section on the line 5 5 of Fig. 3. Fig. 6 is a vertical longitudinal section through a kiln-chamber on the line 6 6 of Fig. 5, and Fig. 7 is a similar view on the line 77 of Fig. 5.

Like reference characters designate corresponding parts throughout the several views. 50 As shown in the annexed drawings, the continuous kiln consists of a series of kiln-chambers arranged, preferably, in two longitudinal

parallel rows or batteries, the chambers of one row being denoted by the numerals 1 to 10, inclusive, and the chambers of the other row 55 by the numerals 11 to 20, inclusive. These chambers may be of any desired size and general construction, and the end chambers 1 and 20 and 10 and 11 are connected by underground and overhead flues A and B, through 60 which the heat and flames circulate from one to the other, thus establishing communication between the two rows of chambers. The space or passage between the two rows of kiln-chambers is of proper width to form a street or 65 driveway for the passage of cars or teams in loading and unloading the chambers and removing the ashes. The overhead flues B are preferably arched to enable the passage of teams beneath them. C is an auxiliary or 70 starting furnace connected with the kiln-chamber 1.

Each kiln-chamber is provided at one end with a furnace D and at the other end with a smoke-stack E and a doorway F, said doorway 75 being closed by a temporary filling of brick when the kiln is in operation. The furnace and smoke-stacks of the adjacent kilns are preferably arranged alternately at opposite ends of the kilns throughout the series, although in large kilns there may be one or more furnaces and a door in each end of each kiln-chamber. The furnaces used may be of the type shown in my United States Letters Patent No. 501,380, dated July 11, 1893, de- 80 signed for using slack and like cheap varieties of fuel, or it may be of any other desired type and construction.

Each kiln is, furthermore, provided with a longitudinal underground flue G, leading to 90 the smoke-stack, said flue having at the top a perforated plate g and at its outer end a damper h, by means of which the flue may be closed to prevent the passage of the flames and gases to the smoke-stack. The flames 95 and gases enter the flue through the perforations in the plate g, and said flue is located adjacent to the farther side wall of the kiln-chamber in the direction of travel of the flames and gases, so that the latter in passing to the flue will be caused to swoop across 100 the floor of the chamber and to come into intimate contact with the ware being burned, whereby thorough burning of the lower

courses or tiers of the ware is insured. The kiln-chambers are in communication with each other at top and bottom through passages formed in their side walls, each kiln 5 of each battery being in communication at top with the next adjacent kiln through a horizontal passage *i*, controlled by a damper *j*, and at bottom through a longitudinal series of horizontal passages *k*, alongside of 10 which is arranged a gutter *l*. Intersecting these passages *k* are vertical feed chutes or passages *m*, through which coal or other fuel may be supplied from the exterior to close 15 said passages *k*, for a purpose hereinafter described. The chutes *m* open to the exterior through the top of the kiln and are closed by suitable lids or covers *n*. At one or both 20 ends of the kiln a stoke-hole *o* is provided in line with the gutter *l*, so that a poker may be introduced to force the coal or ashes away 25 from the passages *k* to clear the same. Vent-holes *p*, having suitable closures *q*, are provided in the top of the kiln-chamber to facilitate the outlet of the heat when cooling the 30 chamber at the end of the burning operation. As heretofore stated, the two rows of kiln-chambers are in communication at their ends by the flues A and B, which establish a continuous circulation.

35 Instead of having a separate smoke-stack E for each kiln-chamber I may, if desired, provide one large smoke-stack and have the underground flues G communicate with the same.

35 The operation is as follows: The kiln-chamber 1 is first filled with the brick or substance to be burned and the flues or passages between the kiln-chambers are closed, the flues *i* being closed by shutting the dampers *j* and the 40 flues *k* closed by filling them with coal or slack, a portion of which rests in the gutter *l*. The flues *k* may be closed from the interior before the doorways F are sealed or from the exterior after said doorways are sealed 45 through the chutes *m*. The doorways are sealed after the kiln is filled with the ware to be burned by filling them up with bricks and mud or suitable cement. The underground-flue dampers *h* are, however, left open to the 50 desired extent to create the necessary draft. When this has been done, fires are started in the starting-furnace C, and the furnace D of the kiln-chamber 1 and the heat and flames therefrom circulate around in the chamber 55 and across the floor thereof and thence pass out to the smoke-stack E through the underground flue G. About twenty-four hours after kiln-chamber 1 is fired the ware to be burned in chamber 2 is placed therein and the door- 60 way of said chamber 2 sealed in the manner before stated. A fire is then started in the furnace or furnaces of kiln-chamber 2, and in twenty-four hours the kiln-chamber 3 is filled and its furnace fired, and so this process is 65 continued, one chamber being filled and fired each day. In about the time required to set and fire several chambers (this period de-

pends upon the kind and condition of the ware being burned) the fuel in flues *k*, between chambers 1 and 2, takes fire and is finally consumed, whereby said flues are opened for the passage of the heat and flames from chamber 1 into chamber 2. At this time the damper *h* in the smoke-stack of chamber 1 or in the flue leading to smoke-stack is closed and the damper *j*, controlling the flue *i* between the two chambers, opened, whereby all the excess heat and the flames from chamber 1 are caused to pass into the top and bottom of the chamber 2, the top currents taking a downward course and the bottom currents sweeping across the floor of the chamber 2, whereby the said chamber is equally heated throughout its entire area and the ware uniformly burned. This operation is repeated as each 85 of the chambers reach the degree of heat required to burn the fuel which closes the passages or flues *k*, and thus the excess heat from one is used to burn the contents of the others following it throughout the series, the heat 90 and flames from the end chambers 10 and 20 of the two batteries of chambers being caused to pass into the other end chambers 11 and 1 through the connecting-flues A and B, so that after all the kiln-chambers have been put in 95 use the excess heat from the chamber 20 will be utilized to assist in heating the chamber 1, thereby obviating the necessity of again using the starting-furnace C until the kiln is again started up after a period of inactivity. 100 A period of one day is generally allowed to elapse between the starting of one kiln and the starting of the next succeeding kiln in regular order; but this period of course depends upon the kind and condition of ware 105 being burned. This operation of firing each successive kiln in regular order is continued until a sufficient number have been placed in working order, it requiring from three to six days to thoroughly dry and burn the contents of a chamber. Then after such a period has elapsed the flues between the kilns fired first are closed and the door or doors and vent-openings opened to allow the said chambers to cool off. When from any cause the 115 temperature of any chamber should fall below a determined point, the temperature may be increased by feeding into said chamber through the chutes *m* a small amount of coal, which will be ignited by the flames and cause 120 the temperature of the interior of the kiln to rise. On commencing the burning operation in chambers 11 and 1 during the regular operation of the kiln it is desirable to run the furnaces of the chambers 10 and 20 for a little longer period than usual in order that the temperature of said chambers 11 and 1 may be quickly brought to the desired high point by the entrance thereinto of the heat and flames from the chambers 10 and 20 through 125 the flues A and B.

It will be seen from the foregoing description that upon the opening of the flues *i* and *k* between two adjacent kilns the heat and

flames from one will pass into the other and not only sweep across the top of the kiln, but also across the bottom thereof, whereby an intense heat at all points is produced and 5 the lower courses of the ware will be burned as effectually as the top and intermediate courses thereof, thereby causing the production of evenly-burned ware of uniform quality throughout. Furthermore, by this mode 10 of circulation of the heat and burning-gases stiff mud or shale-brick and other moisture-laden ware may be quickly and evenly burned without the necessity of subjecting them to the ordinary preliminary process of drying.

15 By using a furnace of the construction shown in my prior patent much better results may be secured on account of the more complete consumption of the products of combustion and the absence of a smoky flame; but 20 any other type of furnace may be used with advantage over a kiln of ordinary construction. Hence I do not limit the invention to the use of any particular type, arrangement, or number of furnaces and reserve the right 25 to make such modifications as fairly fall within the spirit and scope of the invention.

Having thus described my invention, what I desire to claim and secure by Letters Patent is—

30 1. A continuous kiln comprising a series of

kiln-chambers, each chamber having a furnace, a smoke-stack, and a flue having a controlling-damper and leading to the smoke-stack, combined with upper and lower passages between chambers, dampers controlling 35 the upper passages, and means for introducing a combustible element for closing the lower passages, substantially as described.

2. In a continuous kiln, and in combination with adjoining chambers, upper and lower 40 flues connecting the top and bottom portions of the chambers, a damper controlling the upper flue, and means for introducing a combustible element for closing the lower flue or flues, substantially as described. 45

3. In a continuous kiln, and in combination with adjoining chambers, upper and lower flues connecting the top and bottom portions of the chambers, a damper controlling the upper flue, and vertical chutes or passages leading to the lower flues, whereby a combustible substance, such as coal, may be introduced to close said flues, substantially as described. 50

In testimony whereof I have hereunto set my hand in presence of two subscribing witnesses. 55
